UNITED STATES PATENT OFFICE

HYMAN R. SEGAL, OF NEW YORK, N. Y., ASSIGNEE TO SEGAL FOUNDERS CORPORATION,
A CORPORATION OF NEW YORK

RAZOR

Application filed June 4, 1931. Serial No. 541,984.

This invention relates to a functionally and structurally improved razor.

It is an object of the invention to furnish a device of this character, the parts of which 5 may be readily shifted to operative and inoperative positions for the purpose of cleansing and blade removal or application.

A further object of the invention is that of constructing a razor in which the parts 10 may be adjusted so that any desired type of shave will result.

A still further object is that of furnishing an article of this character the parts of which will be few in number and individually simple and rugged in construction, these parts being capable of manufacture by automatic machinery and ready assemblage to furnish an apparatus operating over long periods of time with freedom from difficulties.

20 With these and other objects in mind, reference is had to the attached sheets of drawings illustrating practical embodiments of the invention and in which:

Fig. 1 is a partly sectional side elevation 25 of a razor and showing the parts thereof in closed condition;

Fig. 2 is a similar view of the razor head but showing the parts in open condition;

Fig. 3 is a plan view of the guard; 30 Fig. 4 is a view similar to Fig. 1 but showing a slightly different form of construction;

Fig. 5 is a front view of a razor such as is illustrated in Fig. 4 and showing the parts in open or inoperative condition;

35 Fig. 6 is a sectional view taken along the lines 6—6 in the direction of the arrows of Fig. 4;

Fig. 7 is a partly sectional side view of a 40 razor head mounted to rock in a manner different from that shown in Figs. 4 and 5;

Fig. 8 is a plan view of a blade which may be employed in connection with razors of this type;

Fig. 9 is a face view of a razor with certain 45 of the parts broken away to disclose underlying construction;

Fig. 10 is a sectional side view thereof;

Fig. 11 is a fragmentary sectional view of a structural detail which may be employed; 50 Fig. 12 is a plan view of the guard, and

Fig. 13 is a similar view of the blade.

In the first eight figures the numeral 10 indicates a tube which, as shown in the first three figures, may be polygonal in cross section and adjacent the upper end of which 55 there is mounted a guard 11. Adjacent its lower end, the tube rotatably mounts a knob 12 and disposed within the tube bore is a stem or rod 3 to the upper end of which a clamping plate 14 is pivotally secured, as at 60 15. This clamping plate cooperates with the guard and it will be noted that the latter preferably has a comb portion 16 adjacent which the cutting edge of the blade lies and that protecting and restraining lugs 17 are 65 preferably formed adjacent the ends of this comb.

The blade is to be interposed between the clamping plate and guard and as shown in Fig. 8 has a cutting edge 18, the ends of 70 which are defined by recesses 19. These recesses accommodate the lugs 17 and it will thus be seen that the blade is restrained from moving accidentally in addition to the fact that the corners of the blade are housed in 75 such manner as to prevent injury to the face of the user. The rear edge of the blade is formed with a notch 20 which accommodates the body of the stem 13 and this rear edge of the blade lies adjacent the rear edge portion 80 of the guard.

As shown in Figs. 1 to 3, the clamping plate is formed with a rearwardly extending flange 21 which enters into a groove 22 provided at the rear edge of the guard by, for 85 example, having the material of the guard extending upwardly and inwardly as at 23. Moreover, the pivot 15 is disposed so that the clamping plate may rock transversely of its body and it is thus obvious that as the stem 90 is shifted with respect to the tube and guard, that the flange portion 21 will engage the guard to assure a rocking movement as has been illustrated in Figs. 1 and 2.

This shifting of the stem with respect to 95 the tube and guard is preferably achieved by having the stem end extended and formed with threads as at 24. Similarly, the bore of the knob 12 is threaded and thus, by turning the knob with respect to the tube, projection 100

and retraction of the stem follows. After projection to the position shown in Fig. 2, it is obvious that a blade may be applied to the parts or removed therefrom and that upon 5 stem-retraction occurring, the blade will be firmly clamped against movement to have its cutting edge overlie the comb to properly shave a surface over which it is caused to move.

10 In the form of construction shown in Figs. 4 and 5, the clamping plate is formed with a groove 26 into which an upstanding flange or rail portion 27 extends. This portion preferably forms an integral part of the guard and 15 in this construction, it will be noted that the pivot is disposed in such manner that a longitudinal rocking of the clamping plate will follow as the stem is shifted with respect to the tube. During such shifting, the rail and 20 groove will cooperate to guide the parts as has been clearly shown in Figs. 5 and 6. In these figures the pivot might be eliminated, resulting in a straight shifting of the parts.

In order to cause this shifting, the tube is 25 slidably encircled by a sleeve 28 and a pin 29 is mounted by the sleeve and extends through slots 30 formed in the tube to couple the sleeve with the stem. Moreover, the knob is formed with a screw threaded portion 31 30 for cooperation with a similarly threaded enlargement 32 forming a part of the sleeve 28. Accordingly, by coupling these threads, the stem and clamping plate may be drawn downwardly with the result that the latter 35 may be caused to engage more or less intimately a blade disposed between its upper surface and the upper surface of the guard. However, upon the knob being turned to a sufficient extent, the screw threads 31 will 40 engage from the threads 32 and the sleeve may now be shifted to elevate the stem to the position shown in Fig. 5. Under such conditions, the blade may readily be removed or applied and the parts may be cleaned.

45 The same form of construction is utilized in connection with the device shown in Fig. 7. However, in this form, the flange or rail 33 is preferably rounded and the pivot is disposed to again permit of rocking movements 50 on the part of the clamping plate which movements will be transversely of its body. Consequently, as the clamping plate is lifted out of contact with the guard by shifting the sleeve upwardly, it will rock in the manner 55 shown in Fig. 2 and then disengage from the guard.

Now referring to Figures 9 to 13, it will be noted that the numeral 34 indicates a guard mounted by a tube 33. Extending from the 60 upper face of the guard is an abutment or lug 35 which serves to maintain the blade in position and to cooperate with the clamping plate in a manner hereinafter described. Slidably disposed within the tube is a stem 65 36, the upper end of which pivotally mounts

a clamping plate 37. The side edges of the lug 35 are preferably bevelled as at 38, and the clamping plate is over-weighted or else some other provision is resorted to so that it normally tends to tilt. Thus with the parts in 70 the position shown in Figure 10, it will be obvious that a downward movement of the stem will cause the clamping plate to engage with its edge one of the surfaces 38, and to be guided into cooperation with the upper surface of a blade or the guard plate.

In order that the stem may be shifted in the manner afore brought out, it will be noted that the tube is encircled by a sleeve 39. The inner face of this sleeve may be grooved or else, as has been shown, a second sleeve member 40 may be fixed within the sleeve to move with the stem and prior to such positioning may be formed with a slot 41. This slot extends spirally and a spring-pressed pin 42 is carried by the stem and extends through a slot 43 formed in the tube and has its end riding within the groove or slot of the sleeve. Secured to the tube 33 is a knob 44 which may be knurled, it being thus apparent that an operator by gripping the sleeve with one hand and gripping the knob with the other may effect a ready relative rotation of those parts.

When such rotation is resorted to it is 95 apparent that the slot 41 will cooperate with the pin 42 to shift the latter along the slot 43. This shifting will result in an axial movement on the part of the stem with respect to the tube to thus cause relative movement of the clamping plate with respect to the guard.

It will moreover be noted that the upper end of the slot 43 is offset so that the pin in riding through this tangential portion will cause the stem—in addition to moving longitudinally—to rotate axially. Consequently the clamping plate, in addition to lifting, will turn through an arc of approximately 90° 105 in addition to swinging so that the parts will move from the position shown in Figure 9 to that shown in Figure 10, and vice versa.

As the parts are returned to their normal position the pin rides through or is shifted 115 by the lower end of the slot 41. This lower end is so proportioned that but little movement of the stem occurs as the pin moves through this slot or grooved zone. Consequently proper adjustment of the clamping plate may be had.

As shown in Fig. 13 a blade 45 is employed 120 in connection with this razor and which blade has a central opening 46 of an area such that the abutment may be accommodated. The corners of the blade may be cut out as at 47 125 and the blade itself may be somewhat transversely flexible. Also, if desired, and as shown in Figure 12, the blade may have two cutting edges so as to be reversible. In order that no damage is likely to occur the guard 130

and/or the clamping plate may under these circumstances have their areas extended so as to house and protect the rear and unused cutting edge.

5 Among other advantages derived by the form of construction shown in these figures is that no shifting of the sleeve is necessary as is the case in the structure shown in Figure 5. By simply turning the sleeve with 10 respect to the knob a complete unseating of the parts may occur for the purpose of blade removal and application.

From the foregoing, it will be apparent that, among others, the several objects of the 15 invention as specifically afore noted, are achieved. Obviously, numerous changes in construction and rearrangements of the parts may be resorted to without departing from the spirit of the invention as defined by the 20 claims.

Having described my invention, what I claim as new and desire to secure by Letters Patent is:

1. A single-edge razor including a tube, 25 a stem movable therein, a clamping plate pivotally attached to said stem, a guard mounted on said tube and cooperating with said plate, means for effecting shifting of said stem with respect to said tube, said pivot 30 being arranged to permit transverse rocking of said plate with respect to said stem, and flanges forming parts of said plate and 35 guard and interengaging to effect positive rocking of said elements with respect to each other, as said stem and tube are shifted.

2. A single-edge razor including a tube, a stem movable therein, a clamping plate pivotally attached to said stem, a guard mounted on said tube and cooperating with 40 said plate, means for effecting shifting of said stem with respect to said tube, said pivot being arranged to permit transverse rocking of said plate with respect to said stem, a rail forming a part of said guard 45 and said plate being formed with a groove to guide said elements with respect to each other as said stem is shifted with respect to said tube.

3. A single-edge razor including a tube, 50 a stem movable therein, a clamping plate pivotally attached to said stem, a guard mounted on said tube and cooperating with said plate, means for effecting shifting of said stem with respect to said tube, the pivot 55 for said clamping plate being disposed in such manner that said plate rocks longitudinally as said stem is shifted with respect to said tube, said guard being formed with a rail and said clamping plate being formed 60 with a groove accommodating said rail to guide said clamping plate as said stem is shifted with respect to said tube.

4. In a single edged razor including a tube, 65 a stem movable therein, a clamping plate pivotally attached to said stem, a guard mount-

ed on said tube and cooperating with said plate, means for effecting shifting of said stem with respect to said tube, said pivot being arranged to permit transverse rocking of said plate with respect to said stem, 70 an abutment formed adjacent the rear edge of said guard and said clamping plate being formed with a corresponding recess to guide said parts when the latter is in seated position.

In testimony whereof I affix my signature.
HYMAN R. SEGAL.
